UNITED STATES PATENT OFFICE.

THOMAS VAUGHAN, OF BOSTON, MASSACHUSETTS.

DESIGN FOR CORNERS OF GLASS SHOW-CASES.

Specification forming part of Design No. 7,047, dated December 9, 1873; application filed October 31, 1873.
[Term of Patent 7 years.]

To all whom it may concern:

Be it known that I, THOMAS VAUGHAN, of Boston, in the county of Suffolk and State of Massachusetts, have invented a Design for the lower corners of Glass Show-Cases, of which the following is a specification:

The nature of my design is fully represented in the accompanying illustration, in which—

Figure 1 represents the lower corner of a show-case, and Fig. 2 is a plan view of the same.

a is the corner post. *b b* are the glass front and side, and *c c* are respectively the front and side of the base of the show-case, all thus far constructed as usual. Thus far, show-case corners have been of the shape of a right-angle, or what is usually termed "a square corner," or else the corner has made a "sweep" round, forming an arc of a circle.

In my design for a corner I do not bring the front and side *c c* to a right angle, neither do I describe an arc of a circle; but in accomplish-

ing the corner I produce three surfaces, *c'' c''* *c'''*, besides the original surfaces *c c*, by means of obtuse angles, thus exhibiting what might be denominated a polygonal corner. This corner, being silver or nickel plated, and highly polished, presents a highly-ornamental appearance, especially when the metallic covering is stamped out from a single piece of metal.

A larger or smaller number of the surfaces *c'' c''* *c'''* may be used, if desired, but the number shown seems to be the most practicable.

Having thus fully described my design, what I claim, and desire to secure by Letters Patent, is—

A design for the lower corner of a show-case, in which the said corner, having obtuse angles, produces surfaces *c'' c''* *c'''*, substantially as above described.

THOMAS VAUGHAN.
